UNITED STATES PATENT OFFICE.

JONATHAN PETERSON, OF BROOKLYN, NEW YORK, ASSIGNOR TO COMBINATION
MACHINE COMPANY, OF NEW YORK, N. Y., A CORPORATION OF DELAWARE.

METHOD OF PACKAGING.

1,414,706.

Specification of Letters Patent. Patented May 2, 1922.

Application filed January 28, 1921. Serial No. 440,588.

To all whom it may concern:

Be it known that I, JONATHAN PETERSON, a citizen of the United States, and resident of Brooklyn, in the county of Kings and State 5 of New York, have invented certain new and useful Improvements in Methods of Packaging, of which the following is a specification.

My invention relates to a method of completing or closing containers, such as cartons, 10 and also to a method of packaging goods comprising filling a carton or box body, and forwarding the filled body and applying a cover to it to complete the package.

The general object of the invention is to 15 devise a method, suitable for packages of a certain class which may be rapidly and economically performed, either by hand or machine operations or by a combination of such operations, resulting in a high out-put at 20 moderate cost.

A more particular object is to provide a method suitable for a certain class of cartons and also especially available for goods of a certain class, such as cigarette boxes or packages; although the invention is not limited to 25 the packaging of such articles.

In a companion application Serial No. 440,587 filed January 28, 1921, I have shown and described a container or carton having 30 certain new and desirable characteristics and the present invention is particularly adapted to the handling of filled carton bodies of the character described in that application and the covering or completion of 35 such cartons to form a complete merchandise package.

Broadly described the method comprises the filling of a carton body, usually consisting of relatively thin and flexible paper and 40 having foldable side and end margins, suitably holding or supporting the filled body, applying adhesive to the body margins, associating a cover piece and usually also a 45 filler piece with the body, and bringing the parts into suitable connection, usually by adhesively securing marginal portions of the cover to the body margins and then turning down the combined cover and body marginal portions and securing them to sides and ends 50 of the body by means of the adhesive previously applied to the body margins.

The characteristics and advantages of the invention are further sufficiently described 55 in connection with the following detail description of the accompanying drawing

which shows process steps which constitute one representative performance of the method, representative mechanical devices being indicated for performing certain of the operations. After considering this 60 representative performance of the method, persons skilled in related arts will understand that the method steps may be varied greatly; also that certain of the individual steps and certain groups of operations may 65 be performed independently of other operations. While the operations are usually performed in the order hereafter described, certain of the operations may be performed at other points in the sequence of operations and, 70 therefore, considerable variation is permitted as to the order in which certain of the operations are performed.

In the drawings:

Fig. 1 is a side elevation of different associated devices, shown generally in a diagrammatic way, for one representative performance of the method.

Fig. 2 is a top plan of the same.

Fig. 3 is a perspective view of a carton 80 body, especially available in connection with my method.

Fig. 4 shows the body filled with a suitable commodity, in the present instance with cigarette packages in orderly layer and row 85 arrangement.

Fig. 5 is a bottom plan view of a series of filler pieces associated with a strip of cover paper and also showing a severed assembly consisting of a cover blank and a filler piece. 90

Fig. 6 is a perspective view of two adjacent packages with filler pieces and cover paper in place and connected by the continuous strip of cover paper.

Fig. 7 is a perspective view of a completed package.

Box or carton bodies B, Fig. 3 are provided, of the character described in my companion application above identified. These bodies usually consist of paper or cardboard 100 of relatively thin, or moderately thick material. Usually for the sake of economy the body paper is quite thin so that it does not have any considerable amount of stiffness or rigidity, except when reinforced by the package contents or when properly supported by a suitable holding device during the filling and covering operations. This body comprises a bottom portion 1, side walls 2, end walls 3 and upstanding side 110

margins 4 and end margins 5, these marginal portions being unconnected at the corners of the box.

Such carton bodies are filled with a suitable commodity, such as cigarette packages or boxes A, Figs. 1, 2 and 4, and placed in a suitable holder or carrier 10. These holders are usually arranged in a series, for instance by connecting them to links or blocks 10 of a chain 11, so that a succession of filled carton bodies may be advanced in a series. The holders or carriers usually provide a certain amount of reinforcement and support for the filled cartons and for that purpose they may be desirably formed of metal and desirably also they have side walls 11^a, ends walls 12 and bottom flanges 13 surrounding an opening 14 for a purpose hereafter described. The upper surfaces 15 of the carrier side and end walls are desirably flat and smooth and of substantial width, this width usually corresponding to the vertical width of the carton margins 4 and 5 and these surfaces also lie in the same plane. 20 The surfaces 15 may be cut away so that at the corners of the carrier depressions 16 are formed where the side and end surfaces 15 would otherwise intersect.

In the present instance the holders 10 serve not only as carriers for the filled cartons, but as glue imprinting devices for applying adhesive to the outer faces of the carton margins 4 and 5. For this purpose glue is applied to the holder surfaces 15 and most conveniently this application is made before the filled carton is inserted in the holder. The glue application is provided for in the present instance by a gluing device 20 of any suitable form, the actual device for applying glue to the surfaces 15 consisting in this instance of a glue roll 21 having its periphery arranged to contact with the surfaces 15 of the advancing holders. To this end the conveyor chain 45 or chains 11 may pass about a sprocket or sprockets 22 adjacent to the gluing device. The filled cartons are then inserted at about the point 25, Fig. 1 and they advance in series and the carton margins 4 and 5 are turned down and pressed upon the adhesively coated surfaces 15 of the holders so that these carton margins are gummed by offset from the holder surfaces. This glue receiving contact of the carton margins may be effected by hand or by suitable instrumentalities and a roller 26 is provided in the present instance for insuring proper contact of the carton margins with the holder surfaces. The depressed portions 16 of the holders limit the application of glue to the holder surfaces which correspond with the downturned carton margins and, therefore, there are no glued surfaces of the holder exposed to contact with the 65 pressing roll 26.

It is now desired to complete the package by applying a cover sheet to each of the carton bodies and conveniently the covers are applied in the present instance in the form of a continuous strip of paper so that 70 the cover material for a succession of cartons is connected during a certain part of their travel and at a suitable point the cover strip is severed by suitable means. It is also usually desired to insert a filler piece 75 substantially co-extensive with the open side of the carton body upon the carton contents and under the cover piece. Desirably this is done in the present instance by feeding separate filler pieces under the cover 80 strip so that a filler piece will come into position in the opening of each carton. These objects are desirably accomplished by adhesively coating the strip of cover material and bringing its adhesive surface into 85 contact with the successive filler pieces in such a way that the spacing of the filler pieces agrees with the spacing of the container bodies. The cover paper may be originally gummed on one surface and may 90 be moistened as it is fed toward the point of association with the filler pieces or of application to the carton bodies, or the cover material may be applied prior to its above-mentioned points of association or applica- 95

I will now describe further process steps conforming substantially to the more desirable or convenient condition just above mentioned, but it is to be understood that the next following steps are to a large extent independent of each other and are not to be considered interdependent in the broader aspect of the invention. That is to say, the main essentials of the next ensuing steps are 100 merely the application of cover pieces to the successive cartons, with the incidental insertion of filler pieces when it is desired, although the combined operations are very advantageous and desirable in one performance of the method. 105

A strip of cover paper C, substantially as wide as the lateral dimension of the holders 10, is fed, conveniently from a roll 30, and at a convenient point in its advance it is 110 treated to render one of its surfaces adhesive. When the cover paper is originally glued on one side, that side is moistened by any suitable moistening device 31 and when the paper is unglued, the device 31 is 115 120 any suitable gluing device for applying glue to the surface which is to be presented to the carton bodies. A table or guide plate 35 is placed above the series of holders and at a suitable point filler pieces F are moved over this table and, most desirably, are at the same time moved under the advancing strip of cover material. For this purpose the cover strip is guided by roll 36 under a 125 presser 37 carried by a stem 38 which may 130

be moved in any suitable way at suitable intervals with relation to the progress of the holders. At the point where the cover paper passes beneath the presser it is elevated considerably above the table 35 and at suitable intervals successive filler pieces F are brought between the cover strip and the table and under presser 37. For this purpose a stack of fillers may be arranged in 10 a vertical holder 40 and they may be advanced individually at suitable intervals from the bottom of the stack by a pusher 41. At about the time each filler piece F comes in position the presser 37 is moved down 15 and presses the adhesively coated cover strip upon the filler piece and the cover strip then passes on and another filler piece is secured to it, suitably spaced away from the first, and so on, the spacing of the filler pieces corresponding to the spacing of the 20 cartons in the successive holders. Fig. 5 is a bottom view of a continuous strip of cover paper C, with fillers F secured to it at proper intervals. At a suitable point beyond the 25 table or plate 35 the cover strip is pressed into adhesive engagement with the outwardly turned margins 4 and 5 of the carton bodies, for instance by a roller 40', and at the same time a filler piece is placed in 30 position over the contents of each carton and under the cover strip. The carton is then advanced, connected to others adjacent by the continuous cover strip, as shown in Fig. 6.

35 The cover material is now severed along the line 45 (Fig. 6) midway between two adjacent cartons and this severing may be accomplished in any desirable way, but is conveniently performed by a hot wire 50 arranged transversely and moved into contact with the cover strip at suitable intervals, arms 51 pivoted on a shaft 52 being shown for moving the severing wire. Most conveniently the wire is heated by electric 45 current and conductors 53 are indicated in Fig. 2 for supplying heating current to the wire.

The folded and covered cartons are now desirably removed from the holders whereupon the under surfaces of the body margins 4 and 5 will be available, adhesively coated in the earlier stages of the process by contact with holder surfaces 15, and the package is completed by folding down the combined marginal portions of the cover and body and pressing the adhesive surfaces just mentioned against the sides and ends of the body. In this operation also the corners 60 of the cover which are adhesively coated but unconnected with any portions of the body material are folded in any suitable way either under or over the marginal portions of the body material.

65 The glue or other adhesive is of such composition and consistency, and the speed of

operations is such that the adhesive remains sufficiently soft or moist at the time of removing the body-margins from holder surfaces 15, to permit such removal to be performed easily, and to present the glued surfaces of these margins in proper condition for adhering to sides of the body, in the following operations.

The removal and completion of the packages may be accomplished in any desirable 75 way, but in the present instance these operations are provided for as follows: At a suitable point beyond the severing point a vertical passageway or channel 70 is arranged to receive the successive packages, 80 the side and end walls of this passageway being dimensioned to fit the sides and ends of the packages quite closely, or yieldable pressing and holding devices may be provided when necessary or desirable. Below 85 the succession of holders 10 is arranged an ejector consisting in this instance of a plunger 75 which may be moved up at suitable intervals through openings 14 in the bottoms of the holders. The plunger may be moved 90 by a cylinder 76 to which air under pressure is supplied at proper intervals, through a pipe 77, and exhausted again to retract the plunger. At each stroke the upper end of 95 the plunger engages the bottom of one of the cartons and moves it up into the channel 70 and as it does so the under surfaces of body margins 4 and 5 are stripped away from the adhesively coated surfaces of the 100 holders. The top of the covered carton then passes into the lower end of the channel, this entrance being facilitated by beveled inner surfaces 71 of the channel side and end walls. In entering the vertical channel 105 the projecting flanges composed of margins of the cover and body are smoothed down against the sides and ends of the body material and pressed in position. After the channel 70 is filled each stroke of the plunger 75 ejects a completed package from the 110 top of the channel and these packages may be disposed of in any convenient manner. Fig. 7 shows a completed package produced by the described method.

115 Since the carton comprising only the parts above described forms a complete package closure without the necessity for any outer wrapping, as more fully explained in my companion application previously identified, and since it is often desirable to save the 120 added expense of any additional covering or label, it is desirable in some cases to provide for imprinting upon some part of the carton proper suitable indicia, such as the manufacturer's name, trade-mark or any 125 other desired subject matter. In one performance of the method it is perfectly practicable to make the cover pieces C originally separate or at any rate to cut them apart before application to the carton bodies, and 130

in such a case it is, of course, easy to imprint the desired subject matter upon the outer surfaces of the cover pieces. But in a desirable performance of the method as 5 here particularly described, the cover material is desirably provided in a continuous strip, and it is, therefore, desirable to provide means for imprinting the desired indicia upon this cover strip before application 10 to the individual carton bodies. For this purpose in the present embodiment of the invention a suitable printing device 80 is provided between the point where the cover strip leaves roll 30 and the point 15 where it is adhesively coated or moistened. 81 indicates any suitable printing roller and 82 is an abutment roller. Any suitable printing mechanism may be employed. A suitable interconnection may be provided 20 between the carton holder advancing mechanism and the printing mechanism to insure application of the printed subject matter to the cover strip at such intervals that such subject matter will appear in properly 25 registered position on each of the packages. Such mechanism is not shown in the present application. Otherwise, the printed matter may be of such a nature and repeated in such a way that registry mechanism may 30 be omitted. Fig. 7 shows a printed legend 90 representative of an imprint that may be made by the printing mechanism 80.

Evidently any or all of the described operations may be performed by hand or by the 35 use of implements of elementary simplicity; also, evidently the order of steps is in many instances immaterial; and, therefore, in certain claims where the method is said to comprise certain operations, the order of operations 40 is generally not material unless so described, or unless a stated operation can only be performed after the performance of another one.

I, therefore, do not confine myself to details, except as claimed.

What I claim is:

1. A method of packaging comprising applying adhesive to marginal portions of a container body, applying a cover piece to the 50 open side of the body and securing the cover piece adhesively to said body margins, and turning down the combined cover and body marginal portions and securing the adhesively coated faces of the body margins to 55 adjacent sides and ends of the body.

2. A method of packaging comprising adhesively coating outer surfaces of marginal portions of a carton body surrounding the open side of the body and turning said 60 marginal portions outwardly, placing a filler piece in the open side of the body, applying a cover piece overlying the filler piece and the body margins and adhesively securing marginal portions of the cover to said body 65 margins, and turning down the combined

cover and body marginal portions and securing the adhesive surfaces of the body margins to side and end surfaces of the body.

3. A method of packaging comprising 70 advancing a filled carton body having upstanding margins about its open side, turning said margins outward and imprinting adhesive upon their under faces, applying a cover piece to the open side of the body 75 and securing margins of the cover piece to upper faces of said body margins, and turning down the combined cover and body margins and securing the adhesive under faces of the body margins to sides and ends of the 80 body.

4. A method of packaging comprising advancing a filled carton body having upstanding margins about its open side, turning said margins outward and imprinting 85 adhesive upon their under faces, placing a filler piece upon the contents of the body within the limits of the body walls, applying a cover piece over the filler piece and securing margins of the cover piece adhesively 90 to upper faces of the body margins, and turning down the combined cover and body margins and securing the adhesive under surfaces of the body margins to sides and ends of the body.

5. A method of packaging comprising applying adhesive to marginal surfaces of a carton holder, inserting a carton body in the holder, bringing marginal portions of side and end walls of the carton body into 100 contact with the adhesive surfaces of the holder, applying a cover piece to the open side of the body and securing the margins of the cover piece adhesively to the body margins, removing the carton from the 105 holder and turning down the margins adhesively coated by the holder surfaces and securing them against side and end walls of the carton body.

6. A method of packaging comprising applying adhesive to marginal surfaces of a carton holder, inserting a filled carton body in the holder, bringing marginal portions of side and end walls of the carton body into contact with the adhesive surfaces of the 115 holder, inserting a filler piece upon the carton contents within the limits of the body walls, applying a cover piece over the filler piece and adhesively securing marginal portions of the cover piece to the body margins, 120 removing the carton from the holder and turning down the marginal portions and pressing the surfaces adhesively coated by contact with holder surfaces against sides and ends of the carton body.

7. A method of packaging comprising advancing a series of carton bodies having outwardly disposed marginal portions about their open sides, applying a continuous cover strip to successive cartons and securing the 130

cover strip adhesively to said carton margins and severing the cover strip between adjacent cartons.

8. A method of packaging comprising advancing a series of carton bodies having outwardly disposed marginal portions about their open sides, placing a filler piece in the open side of each carton body, applying a continuous cover strip over the filler pieces and adhesively securing the cover strip to said body margins and severing the cover strip between adjacent cartons.

9. A method of packaging comprising advancing a series of carton bodies having foldable marginal portions about their open sides, applying adhesive to outer surfaces of the body margins, applying a continuous cover strip to successive cartons and securing the cover strip adhesively to said carton margins, and turning down the combined cover and body margins and securing them against sides and ends of the body.

10. A method of packaging comprising advancing a series of carton bodies having outwardly disposed marginal portions about their open sides, applying adhesive to under surfaces of the body margins, placing a filler piece in the open side of each carton body, applying a continuous cover strip over the filler pieces and adhesively securing the cover strip to said body margins and severing the cover strip between adjacent cartons, and turning down the combined cover and body margins and securing them against sides and ends of the body.

11. A method of packaging comprising advancing a series of carton bodies having outwardly projecting margins about their open sides, feeding an adhesively coated cover strip in proximity to the bodies, placing filler pieces adjacent to the cover strip at intervals corresponding to the body intervals and securing the filler pieces to the adhesive surface of the strip, applying the strip to the carton bodies with its adhesive surface in contact with the body margins and with a filler piece located in the open side of each carton body, and severing the cover strip between two adjacent carton bodies.

12. A method of packaging comprising advancing a series of carton bodies having outwardly projecting margins about their open sides, feeding an adhesively coated cover strip in proximity to the bodies, placing filler pieces adjacent to the cover strip at intervals corresponding to the body intervals and securing the filler pieces to the adhesive surface of the strip, applying the strip to the carton bodies with its adhesive surface in contact with the body margins and with a filler piece located in the open side of each carton body, severing the cover strip between two adjacent carton bodies, and adhesively securing the combined cover and

body margins against sides and ends of the body.

13. A method of packaging comprising applying adhesive to circumferential surfaces of a series of holders, placing filled carton bodies in successive holders, the bodies having upstanding side and end margins, turning down the body margins and engaging them with the adhesive holder surfaces, feeding an adhesively coated cover strip in proximity to the succession of holders, and applying it to the upper surfaces of the body margins and severing the cover strip between adjacent carton bodies.

14. A method of packaging comprising applying adhesive to circumferential surfaces of a series of holders, placing filled carton bodies in successive holders, the bodies having upstanding side and end margins, turning down the body margins and engaging them with the adhesive holder surfaces, feeding an adhesively coated cover strip in proximity to the succession of holders, supplying filler pieces adjacent to the cover strip at intervals corresponding to the holder intervals and securing these filler pieces to the adhesive surface of the strip, applying the cover strip to the carton bodies with its adhesive surface engaging the body margins and with a filler piece inserted in each body opening, and severing the cover strip between adjacent carton bodies.

15. A method of packaging comprising applying adhesive to circumferential surfaces of a series of holders, placing filled carton bodies in successive holders, the bodies having upstanding side and end margins, turning down the body margins and engaging them with the adhesive holder surfaces, feeding an adhesively coated cover strip in proximity to the succession of holders, applying it to the upper surfaces of the body margins, severing the cover strip between adjacent carton bodies, removing the carton from the holder and folding down the combined cover and body margins and securing the body marginal surfaces coated by contact with the holder surfaces against surfaces of the body.

16. A method of packaging comprising applying adhesive to circumferential surfaces of a series of holders, placing filled carton bodies in successive holders, the bodies having upstanding side and end margins, turning down the body margins and engaging them with the adhesive holder surfaces, feeding an adhesively coated cover strip in proximity to the succession of holders, supplying filler pieces adjacent to the cover strip at intervals corresponding to the holder intervals and securing these filler pieces to the adhesive surface of the strip, applying the cover strip to the carton bodies with its adhesive surface engaging the body margins and with a filler piece inserted in each body

- opening, severing the cover strip between adjacent carton bodies, removing the carton from the holder and folding down the combined cover and body margins and securing 5 the body marginal surfaces coated by contact with the holder surfaces against surfaces of the body.
17. A method of packaging comprising filling a relatively thin and flexible carton 10 body having projecting margins at its open side, placing the filled body in a reinforcing holder, applying adhesive to outer surfaces of the body margins, inserting a filler piece and applying a cover piece adhesively to the 15 filler piece and inner surfaces of the body margins, removing the package from the holder and turning down the combined cover and body margins and pressing the adhesive surfaces of the body margins 20 against the side surfaces of the body.
18. A method of packaging comprising filling a series of relatively thin and flexible carton bodies having upstanding margins about their open sides, placing the filled 25 bodies in a series of reinforcing holders, applying adhesive to outer surfaces of the body margins, inserting a filler piece in the open side of each body, applying a continuous adhesive coated cover strip to the successive 30 bodies with its adhesive surface in engagement with the filler pieces and with inner surfaces of the body margins, and severing the cover strip between adjacent bodies.
19. A method of packaging comprising filling a series of relatively thin and flexible carton bodies having upstanding margins about their open sides, placing the filled 35 bodies in a series of reinforcing holders, applying adhesive to outer surfaces of the body margins, inserting a filler piece in the open side of each body, applying a continuous adhesive coated cover strip to the successive bodies with its adhesive surface in engagement with the filler pieces and with inner 40 surfaces of the body margins, severing the cover strip between adjacent bodies, removing the cartons from the successive holder, and turning down and securing the outer 45 adhesive surfaces of the body margins 50 against side surfaces of the bodies.
20. A method of packaging comprising advancing a series of carton bodies having outwardly extending margins about their open 55 sides, applying a continuous cover strip in adhesive engagement with upper surfaces of the body margins and applying a heated element to sever the cover strip between adjacent bodies.
21. A method of packaging comprising advancing a series of carton bodies having outwardly extending margins about their open sides, applying a continuous adhesive cover strip in engagement with upper 60 surfaces of the body margins and applying a 65 hot wire to sever the cover strip between adjacent bodies.
22. A method of packaging comprising advancing a series of carton bodies having outwardly extending margins about their open sides, applying a continuous adhesive cover strip in engagement with upper surfaces of the body margins and applying an electrically heated element to sever the cover strip between adjacent bodies. 70
23. A method of packaging comprising applying adhesive to circumferential surfaces of a series of holders, placing carton bodies in the holders and bringing portions of the carton bodies into contact with the adhesive holder surfaces for subsequent 75 package forming operations.
24. A method of packaging comprising advancing a series of filled cartons having outwardly extending margins about their open sides, feeding a continuous cover strip adjacent to the advancing cartons, the strip having an adhesive surface, feeding filler pieces successively under the adhesive surface of the strip and pressing the strip and 80 filler pieces together, and applying the cover strip to the margins of successive cartons with a filler piece located in the open side of each carton under the cover strip. 85
25. A method of packaging comprising advancing a series of filled cartons having outwardly extending margins about their open sides, feeding a continuous cover strip adjacent to the advancing cartons, the strip having an adhesive surface, feeding filler 90 pieces successively under the adhesive surface of the strip and pressing the strip and filler pieces together, applying the cover strip to the margins of successive cartons with a filler piece located in the open side 95 of each carton under the cover strip, and applying a heated element to sever the cover strip between adjacent cartons. 100
26. A method of packaging comprising advancing a series of filled carton bodies, feeding a continuous cover strip adjacent to the body series, applying and securing the cover strip to successive carton bodies, and then severing the cover strip between adjacent bodies. 110
27. A method of packaging comprising advancing a series of filled carton bodies having outwardly extending margins about their open sides, applying adhesive to the under surfaces of the margins, applying a 115 cover piece to the open side of each body with its margins adhesively connected to the upper surfaces of the body margins, and moving the covered bodies successively with the covers in advance and pressing down 120 the combined cover and body margins against sides of the bodies. 125
28. In a method of forming containers of relatively thin and flexible material, in which a cover is applied to the open side of 130

a carton body having projecting margins, the steps consisting in adhesively coating the outward surfaces of the body margins, applying the covers adhesively to the body 5 margins, and turning down the combined cover and body margins and securing them against the sides of the body.

29. In a method of forming containers of relatively thin and flexible material, in 10 which a cover is applied to the open side of a carton body having projecting margins, the steps consisting in applying adhesive to the outward surfaces of the body margins, applying a continuous cover strip adhesively 15 to the margins of a series of bodies, severing the cover strip between adjacent bodies and turning down the combined cover and body margins and securing them against sides of the bodies.
30. In a method of forming containers of relatively thin and flexible material, in 20 which a cover is applied to the open side of a carton body having outwardly projecting margins, the steps consisting in applying adhesive to the under surfaces of the body 25 margins by contact with adhesively coated surfaces of adhesive applying devices, applying a continuous cover strip adhesively to the margins of a series of bodies, severing the cover strip between adjacent bodies and turning down the combined cover and body margins and securing them against sides of the bodies.

margins by contact with adhesively coated surfaces of adhesive applying devices, applying a continuous cover strip adhesively to the margins of a series of bodies, severing the cover strip between adjacent bodies and 30 turning down the combined cover and body margins and securing them against sides of the bodies.

31. In a method of forming containers of relatively thin and flexible material, in 35 which a cover is applied to the open side of a carton body having outwardly projecting margins, the steps consisting in applying adhesive to the under surfaces of the body 40 margins by contact with adhesively coated surfaces of holding devices, applying a continuous cover strip adhesively to the margins of a series of bodies, severing the cover strip between adjacent bodies and turning down the combined cover and body margins and 45 securing them against sides of the bodies.

Signed at New York city, in the county of New York and State of New York, this 25th day of January, A. D. 1921.

JONATHAN PETERSON.
